UNITED STATES PATENT OFFICE.

EDWARD I. HORSMAN, JR., OF NEW YORK, N. Y.

DESIGN FOR A DOLL.

50,658.

Specification for Design. Patented Apr. 24, 1917.

Application filed February 23, 1917. Serial No. 150,590. Term of patent 3½ years.

To all whom it may concern:

Be it known that I, EDWARD I. HORSMAN, Jr., a citizen of the United States of America, residing in the city, county, and State of New York, have invented a new, original, and ornamental Design for Dolls, of which the following is a specification, reference being had to the accompanying drawing, forming a part thereof, which is a perspective view of a doll showing my new design.

I claim—

The ornamental design for a doll as shown.

In witness whereof, I have signed my name to this specification in the presence of two witnesses.

EDWARD I. HORSMAN, Jr.

Witnesses:

M. MORGAN,
FRED STARK.
